CLAIM

The tiltable toilet seat for disabled persons, as shown and described.

DESCRIPTION

FIG. 1 is a perspective view of a tilttable toilet seat for disabled persons showing my new design;

FIG. 2 is a top plan view thereof;

FIG. 3 is a front elevational view thereof;

FIG. 4 is a rear elevational view thereof;

FIG. 5 is a right side elevational view thereof; and

FIG. 6 is a left side elevational view thereof;

FIG. 7 is a bottom view thereof.

The broken line representation of a toilet in FIG. 1 is for purpose of illustration only.

FIG. 2

FIG. 7

FIG. 3

FIG. 5

FIG. 6
